UNITED STATES PATENT OFFICE.

CARL O. McGRAW AND JAMES L. MARTIN, OF ROYSE CITY, TEXAS, ASSIGNEES OF ONE-
THIRD TO FRANK P. HOLLAND, SR., OF DALLAS, TEXAS.

AUTOMATIC VACUUM DEVICE FOR GASOLINE FILLING STATIONS.

1,413,560.

Specification of Letters Patent. Patented Apr. 18, 1922.

Application filed January 6, 1921. Serial No. 435,377.

To all whom it may concern:

Be it known that we, CARL O. McGRAW and JAMES L. MARTIN, citizens of the United States, residing at Royse City, in the county 5 of Rockwall and State of Texas, have invented new and useful Improvements in Automatic Vacuum Devices for Gasoline Filling Stations, of which the following is a specification.

10 The invention relates to an automatic vacuum device for gasoline filling stations.

The object of the present invention is to provide a simple, practical and efficient automatic vacuum device for measuring and 15 delivering gasoline at filling stations and adapted to be adjusted for delivering the gasoline in charges or portions of the desired amount and capable when set to the desired discharging amount and the discharging or 20 delivering hose opened, of continuous operation of filling and discharging until the discharge or delivering hose is closed thereby simplifying the operation of filling stations and lessening the labor and of enabling the 25 operator to attend to other matters while the device is measuring and delivering the gasoline to the purchaser.

A further object of the invention is to provide an apparatus of this character which, 30 while capable of continuous automatic operation until the valve or faucet is closed, will also be equipped with a manually operable device adapted to control the valve mechanism for enabling the discharge of the 35 contents of the measuring receptacle to be checked at any point independently of the automatic means so that a complete control of the operation will be afforded.

Another object of the invention is to provide 40 a gasoline filling device capable of operation by a single vacuum pump and of automatic control by a valve circuit and adapted to enable the wiring to be arranged a sufficient distance from the gasoline to 45 avoid all danger of gas ignition caused by a short circuit or similar wire trouble likely to produce sparking.

It is another object of the invention to provide 50 an automatic gasoline filling and measuring device in which the mechanism will be visible and readily accessible should it be necessary to clean, adjust or repair the same or access required for any other purpose.

With these and other objects in view, the

invention consists in the construction and 55 novel combination of parts hereinafter fully described, illustrated in the accompanying drawings and pointed out in the claims here- to appended, it being understood that various changes in the form, proportion, size and 60 minor details of construction, within the scope of the appended claims, may be re- sorted to without departing from the spirit of the invention or sacrificing any of the ad- vantages thereof.

65 In the accompanying drawings, in which like numerals of reference designate corresponding parts in the several figures:—

Figure 1 is a vertical sectional view of an automatic vacuum gasoline measuring and 70 filling device constructed in accordance with this invention, the parts being in position for filling the receptacle.

Figure 2 is a detail view of a valve operating mechanism illustrating a modification of 75 the invention.

Figure 3 is a detail view of the float and the trip rod.

Figure 4 is a side elevation of the float partly in section.

80 Figure 5 is a detail view of the rotary adjustable float guide.

Figure 6 is an elevation of the complete apparatus showing the vacuum electric switch for controlling the operation of the 85 vacuum pump.

Figure 7 is an enlarged detail view of the switch and vacuum device.

Figure 8 is a detail view of the double throw trigger.

90 Figure 9 is a detail view of the trigger actuating lever.

In the accompanying drawings in which is illustrated the preferred embodiment of the invention, the automatic valve filling de- 95 vice comprises in its construction, a transparent measuring receptacle 1 constructed of glass and preferably of cylindrical form but it may be of any other desired config- 100 uration and instead of employing a trans- parent receptacle, a non-transparent recep- tacle of metal or any other suitable material may be provided. This will render the apparatus practically unbreakable and the re- ceptacle is arranged upon a bottom plate 2 which is mounted upon a supporting casing 3. The supporting casing 3 is preferably ta- 105 pered upward as shown and it may be com-

posed of sections or plates 5 or be constructed in any other desired manner. When constructed of plates or sections the latter are inclined upwardly and inwardly and are riveted or otherwise secured together and they may be mounted upon any suitable foundation or support. The said casing 3 constitutes a housing for a portion of the mechanism as clearly shown in Figure 1 of the drawings. The bottom plate 2 is connected with a top plate 6 by rods or bolts 7 preferably provided at their upper ends with heads and at their lower ends with nuts 9 piercing the top plate 6 and the bottom plate 2 and detachably securing the same to the receptacle 1. The device is also preferably provided with a cover 10 designed to be constructed of any suitable material and preferably of ornamental form and provided at the top with a transparent globe 11 adapted to receive an electric light 12 or other suitable lighting means.

The device is preferably mounted adjacent a gasoline storage tank 13 and the gasoline line which is drawn therefrom by a vacuum pump 14 passes through an inlet pipe 15 having its upper end 16 mounted in an opening in the bottom plate 2 while the lower portion 17 of the inlet pipe extends into the storage tank to a point adjacent the bottom thereof. The storage tank is designed to be opened to the atmosphere by a suitable venting and filling means 18 and when the air within the receptacle and the inlet pipe is exhausted by the vacuum pump, the atmospheric pressure will force the gasoline into the receptacle 1 as will be readily understood. The filling device may of course be arranged any suitable distance from the storage tank and the inlet pipe 15 is provided at its upper end 16 with a ball check valve 19 which automatically closes under atmospheric and liquid pressure while the device is discharging through the adjustable hose 20. The adjustable hose 20, which is provided at its outer end with the usual cut off faucet or valve 21, is flexibly connected at 22 to an outlet pipe 23 preferably of elbow form as shown in Figure 1 and provided with an automatic outwardly opening valve 24. Also instead of arranging the faucet or valve 21 at the outer end of the flexible hose 20, this valve or faucet 21 and the check valve 24 may be arranged at any other desired points. The valve 24, which is hinged at the top, closes against a suitable seat 25 when the vacuum pump is in operation and gasoline is being drawn from the receptacle 1. The vacuum tube or pipe 26 which is connected at the outer end with the vacuum pump extends into the base casing 3 at the bottom thereof and passes upwardly through said casing 3 exteriorly of the receptacle 1 to the cover 10 which is hollow and which forms a cap for the receptacle. The vacuum tube is connected with a nipple or flange 27 of an opening 28 in the head or top plate 6. The nipple 27 is provided with a valve seat and is adapted to be closed by an upwardly seating valve 29 consisting of a head and a stem 30 extending downwardly from the head and pivoted at the lower end at 31 to a valve actuating lever 32. The stem of the valve 29 operates in a suitable guide 33 in the nipple 27 and the valve actuating lever 32 is fulcrumed intermediate of its ends on a suitable pin or pivot 34 between lugs or ears 35 of a stud or bolt 36 which pierces the head or top plate 6 and is threaded at its upper end for the reception of the nut as shown. The stud and the ears or flanges 35 constitute a hanger or support for the valve actuating lever but the latter may be mounted in any suitable manner as will be readily understood. The valve 29 controls the vacuum tube 26 and the said lever 32 also carries a downwardly seating valve 37 consisting of a head or body and a stem 38 which is pivoted at 39 to the valve carrying and actuating lever 32 adjacent to one end thereof. The valve body or head of the valve 37 is located at the upper end of the stem 38 which extends through an opening 40 in the head or top plate 6. The head or top plate 6 is provided at the opening 40 with a valve seat and when the lever 37 is opened the measuring receptacle 1 is connected through the opening or passage 40 with the atmosphere. The valve 37 is located above its valve seat while the valve 29 is located below its valve seat and when the arm of the lever carrying the said valves is moved upwardly the valve 29 is closed and the valve 37 is opened. When the valve carrying arm of the lever 32 is swung downwardly the valve 29 is opened and the valve 37 is closed. The valve 37 constitutes a vent valve and when the valve carrying arm is moved upwardly air under atmospheric pressure is admitted to the receptacle 1 for permitting the liquid contents of the receptacle to discharge therefrom until the valve carrying lever 32 is operated to change the positions of the valves 29 and 37.

The valve carrying arm of the lever 32 is operated in its upward movement by a float 40^a to close the vacuum tube or pipe and open the vent passage or opening. When this operation takes place, the vacuum pump 14 continues its operation until the air is exhausted from a bellows 70 which operates an electric vacuum switch hereinafter described and opens the circuit 71 in which an electric motor 72 is arranged and thereby stops the operation of the vacuum pump. By this operation, the device will operate continuously and automatically as long as there is liquid in the storage tank or until the valve or faucet 21 of the discharge hose is closed. The

receptacle may be of any desired capacity and the quantity of liquid discharged at each operation of the device may be varied as hereinafter fully explained so that the required amount will be discharged and the operation continued until the desired quantity of the gasoline is measured and delivered.

The float 40^a which may be of any desired construction is provided with a central rectangular opening 42 and it moves vertically within the receptacle 1 until it is limited in its upward movement by contact with an arm 43 of a vertically movable rod 15 or tripping member 44. The float is guided in its vertical movement by a rotary adjustable squared standard or guiding member 45 which has its lower portion 46 reduced to form a stem and journaled in an opening 47 of the bottom plate 2. The stem extends below the bottom plate and through a stuffing box 48, which may be of any desired construction. The stuffing box 48 is shown consisting of a packing nut mounted on a 20 threaded flange or nipple 49 of the bottom plate. The stuffing box prevents leakage of the gasoline and the stem 46 of the vertical guide 45 is journaled in the bottom plate to permit an adjustment of the float for controlling the amount of the discharge of the 25 liquid from the receptacle.

The vertically movable tripping rod or member 44 is guided at its lower portion in a drain pipe 50 and is pivoted at the top at 30 51 to the outer end of the valve carrying arm 51 of the lever 32. The arm 43 which is arranged in the path of the float is preferably L-shaped as shown and it is adjustably mounted on the tripping rod at 52 and is 35 adapted to clamp the same whereby it is secured in its adjustment. The L-shaped arm 43 extends horizontally from the tripping rod and then downwardly over the float and is preferably equipped with an anti-friction 40 roller or wheel 53, which is directly engaged by the float and when the float arrives near the limit of its upward movement it engages the rollers 53 and lifts the tripping rod 44 and swings the valve carrying arm of the 45 lever upwardly. This will cause the lever to reverse the valves and stop the operation of the motor and open the vent passage 40 and permit the gasoline to discharge from the receptacle 1. The rear end of the lever 50 52 is connected by a suitable pivot 54 with one end of a rod or member 55 slidable in an opening 56 in a horizontal pivot 57 and having mounted on it a coiled spring 58^a which is interposed between the rear end of 55 the lever 32 and the pivotal member 56. The pivotal member 56 is mounted between spaced sides of a bracket 59^a and when the rear end of the lever is oscillated from the position shown in Figure 1, it will be moved 60 downwardly and the coiled spring 58 will be

compressed until the lever reaches a horizontal position and the continued downward movement of the rear end of the lever carries the pivot 54 of the lever and the adjacent end of the spring below a horizontal position and the tension of the spring will thereby maintain the lever and the valves in such position until the lever is oscillated to swing its rear end to a position above the horizontal plane of the pivot 34. When the 70 rear end of the lever 32 is carried above such position the spring will operate to hold the lever against movement and the vacuum valve will be opened and the vent valve closed as shown in Figure 1.

The bracket which is provided with a stud or bolt 60^a is secured to the head of the top plate 6 and depends therefrom and the transverse pivot in which the rod 55 slides is adapted to rock in suitable bearings of the 80 spaced sides of the bracket 59^a.

As the liquid discharges from the receptacle 1 the float descends and if it is desired to empty less than the entire contents of the receptacle 1 at each operation of the 90 device, the float is adjusted to carry a tripping arm 58 into the path of one of the arms 59 of the vertically movable trigger rod 44. The arms 59 of the trigger rod are provided at their inner ends with heads having opening 60 to receive the rod 44 and provided with clamping screws 61 for securing the arms in proper position on the rod 44. The arms gradually increase in length from the top to the bottom of the series and 100 are of sufficient difference in length to permit the float to be set to engage any one of the arms of the series. The rod 44 is shown equipped in the accompanying drawings with five arms, the first being set for discharging a gallon of the contents of the receptacle, the second arm being set for discharging two gallons, the third for three gallons, the fourth for four gallons and the fifth arm for five gallons. By this arrangement, the device may be set for discharging any number of gallons between one and 5 at each operation of the device. The rotary adjustment of the guide 45 and the float 110 enables the tripping arm 58 to be set so that in descending from the uppermost position of the float it will engage with one of the arms 59 of the rod or member 44. The opening of the float and the guide may be of any polygonal shape and any suitable 115 anti-friction means may be employed if desired. The float is adjusted by means of an arm 63 suitably connected at its inner end to the lower end of the stem 46 of the vertical guide 45, the outer portion of the operating arm 63 terminating in a handle or guide 64 and extends through a horizontal slot in one of the sides of the base casing. The operating arm 63 is provided at the 120 lower edge with a lug or projection 66 which 125

130

is adapted to extend into any one of a series of notches 67 formed in the base casing at the bottom of the slot 65 and corresponding to the several positions of the float for arranging the trip arm 58 to engage the trigger arm 59. The base casing is designed to be provided at the notches or recesses 67 with numeral designations 68 so that the operating arm may be readily arranged in 10 the desired notch or recess of the slot 65 of the base casing.

The drain pipe is provided with a suitable valve 69 adapted to be opened to permit gasoline to drain from the receptacle 1 back to the storage tank. A valve 69 is 15 normally closed and is spaced from the bottom plate 2 a sufficient distance to permit the lower portion of the rod 44 to be guided in the upper portion of the drain pipe. The 20 discharge hose or pipe 20 is of the usual construction and in practice means will be provided for supporting the same in an elevated position as shown in Figure 1.

In order to enable the discharge of the 25 liquid from the measuring receptacle 1 to be manually controlled and the discharge stopped at any desired point by the tripping of the valve mechanism, the device is provided with valve tripping mechanism comprising a bell crank lever 105 fulcrumed at its angle in a suitable bracket or support 106 having one of its arms arranged horizontally above the vent valve and the other arm of the bell crank lever 105 extends upwardly and is arranged in a vertical position when the other arm is in a horizontal position. The horizontal arm is rounded at the end as shown for engaging the vent valve and a flexible connection such as a chain 107 30 is attached to the upwardly extending arm of the bell crank lever for enabling the latter to be rocked on its pivot for engaging the vent valve to move the same to its closed position. This will swing the spring 58 35 to the opposite side of the center and the valve mechanism will be thereby maintained in such shifted position. The chain 170 is preferably arranged on a guide pulley 108 and is provided at its outer or free end with 40 a suitable handle or grip 109 which may be in the form of a ring as shown or of any other suitable construction. When the valve mechanism is tripped by the manually operable means, the closing of the vent valve 45 and the opening of the vacuum valve will cause a refilling of the measuring receptacle.

The bellows 70 which may be of any desired construction is mounted upon a base 60 73 and is provided with an intake pipe 74 which extends from the bellows to the vacuum pipe or tube 26 so that the continued operation of the vacuum pump 14 after the vacuum pipe or tube has been closed by 65 the valve 29 and the vent opened by the

valve 35 will exhaust the air from the bellows and close the same and move the upper board or member 75 downward. This closing of the bellows by the action of the vacuum pump moves downwardly a link 76 70 pivoted at its lower end at 77 to the upper board or member of the bellows and at its upper end 78 to one end of a trigger actuating lever 79. The trigger actuating lever 79 is pivoted at 80 to a depending post or support 81 provided at its upper end with a threaded shank 82 and secured by a nut in an opening in a fiber insulating head or plate 83. The fiber insulating plate 83 is supported above the case in spaced relation 80 with the same by corner rods 84 which may be of any desired construction and which are suitably secured at their terminals to the base 73 and to the insulating plate or head 83. The closing movement of the bellows 85 incident to the exhausting of the air therefrom and the creating of a vacuum therein is controlled by a tension device consisting of a rod 85 pivoted at its lower end 86 to the upper board or member 75 of the bellows 90 and extending through an opening 87 of the fiber head and having a coiled spring 88 disposed on its upper portion and interposed between the fiber head or plate 83 and an adjusting nut 89. The nut 89 is 95 mounted on a threaded portion 90 of the rod 85, a washer being preferably interposed between the nut and the upper end of the tensioning spring as shown.

The lever 79 is connected by a fiber insulating link 91 with a trigger member or lever 92 fulcrumed at one end by a pin 93 to a supporting and binding post 94 and connected by side springs 95 with a trigger member or lever 96 carrying a contact 97. The lever 79 100 is provided with a projecting lug 98 for engaging the trigger member 92 to limit the downward movement of the same and the said trigger member 92 is bifurcated at its inner end as shown to straddle the binding 105 posts 94 and the adjacent end of the trigger member or lever 96. The trigger members or levers 94 and 96 are provided at their outer or free ends with laterally extending arms 99 and 100 having hook-shaped terminals for 110 the attachment of the ends of the side springs 95. The trigger members constitute a double trigger and are adapted to swing upwardly and downwardly a sufficient distance to carry their terminals and the side springs 115 connected therewith above and below the horizontal plane of the fulcrum or pivot whereby the springs are operated to maintain the trigger members in either position. When the trigger members or levers are 120 swung upwardly the contact 97 which is preferably a predetermined point is carried into electrical engagement with a binding post 101 for closing the support 71 to start the electric motor 72 and operate the 125 130

vacuum pump 14 and when the trigger members or levers are swung downwardly, the contact 97 is carried downwardly out of engagement with the binding posts 101 and the contact portion thereof to open the circuit 71 and stop the electric motor. When the electric motor is in operation the air as heretofore explained will be exhausted from the receptacle 1 which will 10 fill and operate the said valves 29 and 35 and the continued operation of the vacuum pump will tend to produce a vacuum within the bellows and will effect a closing movement of the same sufficient to operate 15 the vacuum switch mechanism and open the circuit 71. The current for the circuit 71 may be supplied from any suitable source and the electric motor while shown connected with the vacuum pump by sprocket 20 gearing 102 may be connected with the said pump by any other suitable gearing and instead of employing a bellows, any equivalent expansible and contractile means such as a piston and cylinder or the like may be 25 utilized for operating the vacuum switch mechanism.

The invention provides a visible pump allowing the customer to see whether or not he is getting the amount of liquid for which 30 he is to pay. The measurements of the liquid are absolutely accurate and the automatic device renders the measurements of each indicated operation uniform so that no guess work whatever is involved. The invention 35 also provides a labor saving device since the turning of the faucet at the end of the delivery hose starts the machine which continues its automatic operation thereafter until the said faucet is closed.

40 The glass receptacle is filled after each operation thereby saving the time usually required for filling such a receptacle after a customer drives up to a filling station. If the glass receptacle is constructed to contain only five gallons, it will be impossible 45 to supply more than five gallons in the receptacle as the automatic action automatically cuts off the flow when the receptacle has been filled. Also the pump being a 50 vacuum pump no air is required in the storage tank thus obviating any and all danger of explosion in the storage tank.

Also the pump being a vacuum pump employing a vent in the glass receptacle to 55 permit the liquid to gravitate into any other receptacle from the said vent permitting air to pass into the said receptacle removes all danger of the glass receptacle bursting from gas which might form from 60 heat or other cause. The gasoline filling station is absolutely safe from explosions from electric ignition since the electric motor and all the electrical wiring can be placed at any distance from the gasoline. 65 For example, the motor and the electrical

switch device may be placed in a building separate from and a considerable distance away from the pump or storage tank. The pump will supply the customer with any number of gallons or fractional gallons and 70 requires only one simple adjustment, the other operations of the device being entirely automatic.

The gasoline cannot be stolen from the storage tank, and by draining the glass receptacle and by opening the vacuum cock, which may be kept under lock and key the motor may be started but no gasoline will rise in the glass receptacle. One motor and one pump and one automatic electrical device 75 may be employed to operate a plurality of the pumps, thereby saving the cost of supplying and installing individual motors, vacuum pumps and electrical switches for each gasoline filling device. The invention 80 is simple and easily constructed and not likely to get out of order and can be manufactured as cheaply as the ordinary gasoline filling station and can be operated by any person who can turn a simple faucet 85 at the end of a hose.

In Figure 2 of the drawings is illustrated a modification of the invention in which the valve carrying lever 110 is fulcrumed intermediate of its end at 111 in a suitable 95 bracket or support 112 and the front arm of the lever 110 is connected with stems 113 and 114 of vacuum and vent valves 115 and 116. The stem 114 is preferably slotted at 117 to receive the pivot 118. The rear end 100 of the valve carrying and actuating lever 110 is provided with an anti-friction wheel 119 which is arranged to ride upon oppositely inclined faces 120 of a head 121 of a 105 slidably mounted stem or member 122 which is yieldably maintained in engagement with the roller or wheel 119 by a coiled spring 123. The coiled spring 123 is mounted on a reduced portion 124 of the stem 122 and is interposed between an interior shoulder 110 of a sleeve 125 and the shoulder formed by reducing the stem. The rear terminal 126 of the stem is threaded to receive a nut 127 which is adapted to control the tension of the coiled spring of the device. The sleeve 115 125 is exteriorly threaded at 128 to engage a threaded opening 129 of a bracket or support 130. The sleeve is provided adjacent the head 121 with an enlargement or flange 120 and the threaded mounting of the sleeve 120 provides for a longitudinal adjustment of the device to arrange the same in proper position to the roller of the rear end of the lever 110 and the adjustment of the stem 125 controls the tension of the spring. In the 125 operation of the lever the roller rides over the oppositely inclined faces 120 and after passing the center will be maintained at either side of the center by the action of the spring 123.

The operation of the apparatus is as follows:

Should the receptacle be empty, the float will be at the lowest limit of its movement 5 and should the current be turned on, the vacuum pump will operate by reason of the pump circuit being closed by the inflation or expansion of the bellows 70 by reason of its connection with the atmosphere. This 10 will cause the receptacle to fill and the float to rise until it reaches the limit of its upward movement which will result in the shifting of the vacuum and vent valves 29 and 37. The vacuum valve will then be closed 15 and the continued operation of the pump will exhaust the air from the bellows 70, and open the circuit and thereby stop the pump. The opening of the vent valve 37 by the said operation places the receptacle in 20 communication with the atmosphere so that the receptacle will automatically empty when the outlet or discharge valve 21 is lowered and opened. As soon as the receptacle empties or discharges the required 25 amount of liquid, the arm 58 of the float will engage one of the arms 59 of the vertically movable float 40 and reverse the positions of the vacuum and vent valves 29 and 37. This will close the receptacle to 30 the atmosphere and establish a communication between the receptacle and the vacuum pipe and the atmospheric pressure within the receptacle will reduce the vacuum within the bellows 70 sufficiently to permit the 35 spring 88 to expand the bellows to the position shown in Figure 7 of the drawings and close the circuit and again start the vacuum pump. The vacuum pump will fill the receptacle and the operation will continue automatically filling and emptying the receptacle until the discharge valve is closed. In 40 this automatic filling and emptying, the apparatus may be arranged to deliver the full capacity of the receptacle at each discharge or the arms 59 may be positioned to reduce 45 the amount of the discharge as will be readily understood. Should the receptacle be discharging and it be desired to reverse the positions of the vacuum and vent valves 29 and 37, this may be manually effected by 50 pulling the operating member 107 for swinging the bell crank lever 105 into engagement with the vent valve to move the latter downward to the position shown in Figure 55 1. This will reverse the positions of the valves 29 and 37 and the apparatus will again start filling the receptacle. No claim is made in the present application to the specific construction of the double electric 60 switch and the vacuum controlling device as this forms the subject matter of a divisional application.

What is claimed is:—

1. An apparatus of the class described 65 having valved inlet and discharge pipes,

said receptacle being also provided with a vent, vacuum producing means connected with the receptacle, simultaneously operated valves for controlling the vacuum means and the vent when the receptacle fills and empties, 70 and means for automatically operating the latter valves.

2. An apparatus of the class described having valved inlet and discharge pipes, said receptacle being also provided with a 75 vent, vacuum producing means connected with the receptacle, simultaneously operated valves for controlling vacuum means and the vent, and means for automatically operating the latter valves, said valve operating 80 means comprising a float and mechanism actuated by the float for closing the vacuum valve and opening the vent valve on the upward movement of the float and for reversing the said position of the said valves on 85 the downward movement of the float.

3. An apparatus of the class described having valved inlet and discharge pipes, said receptacle being also provided with a vent, vacuum producing means connected 90 with the receptacle, simultaneously operated valves for controlling the vacuum means and the vent, and means for automatically operating the latter valves, said valve operating means comprising a pivoted valve carrying 95 lever connected with the said valves, and yieldable means connected to said lever and arranged to be carried to opposite sides of the pivot point of the valve carrying lever.

4. An apparatus of the class described having valved inlet and discharge pipes, said receptacle being also provided with a vent, vacuum producing means connected with the receptacle, simultaneously operated valves for controlling the vacuum means and the 100 vent, means for automatically operating the said valves including a lever connected with said valves, yieldable means connected with the said lever and arranged to be carried to opposite sides of the pivotal point of the 105 lever, a float, and means actuated by the float for oscillating the lever to reverse the position of the valves.

5. In an apparatus of the class described including a receptacle having reversely movable valves for controlling the inlet and discharge of liquid, a lever connected with the valves, yieldable means connected with the lever and arranged to be carried to opposite sides of the fulcrum of the lever for holding the lever and the valves against movement, and means for automatically operating the valves comprising a float, a vertically movable rod or member connected with the said lever and provided with a plurality of trigger arms arranged to be engaged by the float, and means for adjusting the float for operating the trigger arms. 115

6. In an apparatus of the class described including a receptacle having reversely mov- 120

able valves for controlling the inlet and discharge of liquid, a lever connected with the valves, yieldable means connected with the lever and arranged to be carried to opposite sides of the fulcrum of the lever for holding the lever and the valves against movement, and means for automatically operating the valves comprising a float having a tripping arm, and a vertically movable rod or member connected with the said lever and provided with a plurality of trigger arms of different lengths adapted to engage the tripping arm of the float.

7. In an apparatus of the class described including a receptacle having reversely movable valves for controlling the inlet and discharge of liquid, a lever connected with the valves, yieldable means connected with the lever and arranged to be carried to opposite sides of the fulcrum of the lever for holding the lever and the valves against movement, means for automatically operating the valves comprising a float having a tripping arm, and a vertically movable rod or member connected with the said lever and provided with a plurality of trigger arms of different lengths adapted to engage the tripping arm of the float, a vertical guide for the float and means for adjusting the guide for changing the positions of the trigger arm of the float.

8. An apparatus of the class described including a receptacle having a vent and vacuum producing means connected with the receptacle, simultaneously operated valves for controlling the vacuum means and the vent, means for automatically operating the said valves comprising a pivoted lever, a vertically movable rod or member connected with the lever and provided with a plurality of trigger arms of different lengths, a float having a tripping arm for engaging the said trigger arms, a vertical standard forming a guide for the float and journaled for rotary movement, and an operating arm connected with the standard.

9. An apparatus of the class described including a receptacle having a vent and vacuum producing means connected with the receptacle, simultaneously operated valves for controlling the vacuum means and the vent, means for automatically operating the said valves comprising a pivoted lever and provided with a plurality of trigger arms of different lengths, a float having a tripping arm for engaging the said trigger arms, a vertical standard forming a guide for the float and journaled for rotary movement, an operating arm connected with the standard, and yieldable means for maintaining the valves in either position of the lever.

10. In an apparatus of the class described including a receptacle having a vent and vacuum producing means, vent and vacuum valves, an inlet pipe, a discharge pipe, and

means for automatically shifting the valves to change the position of the same when the receptacle fills and empties.

11. A device of the class described including a receptacle, a casing supporting the receptacle and provided with a horizontal slot having a plurality of notches, valved inlet and discharge pipes connected with the receptacle, means for varying the pressure within the receptacle, vent and vacuum valves, means for operating said valves comprising a float having a tripping arm, a trigger rod or member provided with a plurality of triggers, a standard journaled for rotary movement and forming a guide for the float, and an arm connected with the standard and extending through the said slot for adjusting the position of the float with respect to the arms of the trigger rod or member.

12. A device of the class described including a transparent receptacle having valved inlet and outlet pipes, means for varying pressure within the receptacle, simultaneously movable valves for controlling the pressure changing means and means for operating the valves including a float arranged within the receptacle and having a tripping arm, a vertically movable trigger rod or member provided with a plurality of arms and also arranged within the said receptacle, means for connecting the trigger rod or member with the said valves, and means for effecting a relative adjustment between the trigger arms and the tripping arm.

13. A device of the class described including a base casing, a receptacle mounted upon the said casing, valved inlet and discharge pipes connected with the receptacle, a drain pipe having a valve and connected with the receptacle, means for varying the pressure within the receptacle for filling and discharging the same, valves for controlling the pressure varying means, and means for operating the valves comprising a float, and a trigger member guided by the drain pipe and arranged to be actuated by the float.

14. A device of the class described including a receptacle having inlet and discharge pipes, means including a motor operated vacuum pump for varying the pressure within the receptacle for filling and emptying the same, valves for controlling the pressure within the receptacle, means for automatically operating the valves when the receptacle fills and empties and a circuit including the motor of the vacuum pump having a switch arranged to be operated by the said device whereby a continuous automatic operation of the device is effected while the discharge pipe is open.

15. A device of the class described comprising a base casing, a superimposed transparent receptacle, head and bottom plates arranged at the top and bottom of the re-

- ceptacle and connected with each other, valved inlet and discharge pipes connected with the receptacle and mounted in the bottom plate, a drain pipe also connected with 5 the receptacle and mounted in the bottom plate, vacuum producing means having a vacuum pipe extending to the top plate, said top plate being also provided with a vent, valves operating in the top plate for controlling the vacuum tube and the vent, and means for operating the said valves.

16. A device of the class described comprising a base casing, a superimposed transparent receptacle, head and bottom plates 15 arranged at the top and bottom of the receptacle and connected with each other, valved inlet and discharge pipes connected with the receptacle and mounted in the bottom plate, a drain pipe also connected with the receptacle and mounted in the bottom plate, vacuum producing means, having a vacuum pipe extending to the top plate, said top plate being also provided with a vent and valves operating in the top plate for controlling the 25 vacuum pipe and the vent, means for operating the said valves, and a cap mounted on the top plate and provided with a bowl arranged to receive a light.

17. An apparatus of the class described 30 including a receptacle having valved inlet and discharge pipes and provided also with a vent and having a vacuum pipe, automatic means for controlling the vent and vacuum pipe operating when the receptacle fills and 35 empties and vacuum producing means comprising a pump, a motor for operating the pump, a vacuum controlled device connected with the vacuum pipe and adapted to be operated by the pump when the vacuum pipe 40 is closed to the receptacle and means controlled by the vacuum controlled device for starting and stopping the motor.

18. An apparatus of the class described including a receptacle having valved inlet and 45 discharge pipes and provided also with a vent and having a vacuum pipe, automatic means for controlling the vent and vacuum pipe operating when the receptacle fills and empties, and vacuum producing means comprising a pump, a motor for operating the 50 pump, a vacuum controlled device connected with the vacuum pipe and adapted to be operated by the pump when the vacuum pipe is closed to the receptacle and means including an electrical switch connected with and 55 actuated by the vacuum controlled device for starting and stopping the motor.

19. An apparatus of the class described including a receptacle having valved inlet 60 and discharge pipes, vent and vacuum valves, automatic means within the receptacle and operated when the receptacle is empty or full for controlling the said valves for permitting the receptacle to fill and empty, 65 vacuum producing means connected with the

receptacle for filling the same and means for automatically stopping the vacuum producing means when the vacuum producing means is cut off from the receptacle.

20. An apparatus of the class described 70 including a receptacle having valved inlet and discharge pipes, vent and vacuum valves, automatic means within the receptacle and operated when the receptacle is empty or full for controlling the said valves for permitting the receptacle to fill and empty, 75 vacuum producing means connected with the receptacle for filling the same and means for automatically stopping the vacuum producing means when the receptacle has been 80 filled, and means for automatically starting the vacuum means when the vacuum producing means is cut off from the receptacle.

21. In an apparatus of the class described including a receptacle having a vent and 85 vacuum producing means, vent and vacuum valves, an inlet pipe, a discharge pipe, means for automatically shifting the valves to change the position of the same when the receptacle fills and empties, and manually 90 operable means for operating the valves.

22. In an apparatus of the class described including a receptacle having a vent and vacuum producing means, vent and vacuum valves, an inlet pipe, a discharge pipe, means 95 for automatically shifting the valves to change the position of the same when the receptacle fills and empties, and manually operable means for operating the valves comprising a lever having an arm arranged to 100 engage one of the said valves and an operating device connected with the lever.

23. In an apparatus of the class described including a receptacle having a vent and vacuum producing means, vent and vacuum 105 valves, an inlet pipe, a discharge pipe, means for automatically shifting the valves to change the position of the same when the receptacle fills and empties, and manually operable means for operating the valves comprising 110 a bell crank lever arranged to engage one of the valves and a flexible connection attached to the other arm and extending exteriorly of the machine.

24. An apparatus of the class described including a receptacle having an inlet and a discharge pipe and provided with a vent and vacuum producing means, vacuum and vent valves, a lever connected with the said valves and adapted to be oscillated to reverse the 120 said valves, one of said valves being open while the other is closed, and a spring actuated device for holding the lever at either side of a central position.

25. An apparatus of the class described 125 including a receptacle having an inlet and a discharge pipe and provided with a vent and vacuum producing means, vacuum and vent valves, a lever connected with the valves and adapted to be oscillated to reverse the posi- 130

tion of the valves, a rod or member pivoted to the lever, means for slidably and pivotally mounting the rod, and a spring for urging the rod in one direction.

- 5 26. An apparatus of the class described including a receptacle having an inlet and a discharge pipe and provided with a vent and vacuum producing means, vacuum and vent valves, a lever connected with the valves
10 for reversing the position of the same, a pivot having an opening, a rod or member slidably in the opening of the pivot and piv-

otally supported by the same, said rod or member being pivotally connected to the lever, and a spring mounted on the rod or member and arranged to urge the same in the direction of the said lever whereby the spring will maintain the lever at either side of the central position.

In testimony whereof we hereunto affix our 20 hands.

CARL O. McGRAW.
JAMES L. MARTIN.
